UNITED STATES PATENT OFFICE.

EDWIN O. BRANINGTON, OF ROCHESTER, NEW YORK, ASSIGNOR OF ONE-HALF TO
OSCAR A. PETERS, OF ROCHESTER, NEW YORK.

EGG TRAY FOR INCUBATORS.

Application filed February 15, 1924. Serial No. 693,142.

To all whom it may concern:

Be it known that I, EDWIN O. BRANINGTON, a citizen of the United States, and a resident of Rochester, in the county of Monroe and State of New York, have invented a new and Improved Egg Tray for Incubators, of which the following is a specification.

The present invention relates to incubators and more particularly to the egg supporting trays, an object of the invention being to provide a tray having manually operable devices by which the eggs may, as is necessary for a successful hatching, be periodically turned over and in such manner as to effect an even turning of all the eggs and without jarring them or the danger of cracking the shells.

Another object of the invention is to provide a tray of rigid yet light construction and having a bottom that, while sufficiently perforated to permit proper ventilation and circulation of the heated air currents, will not sag under weight of a full capacity of eggs.

And, another object of the invention is to provide an egg tray of the character described that is readily assembled, inexpensively constructed and in which the turning devices are so arranged as not to interfere with its being filled to a capacity limited only by the area within its side walls.

To these and other ends the invention consists of certain parts and combinations of parts as will be fully set forth in the following description and particularly defined in the appended claims.

The accompanying drawings illustrating the invention and forming a part of the specification are as follows:—

Figures 1 and 2 are top and bottom plan views, respectively, of the tray.

Fig. 3 is an enlarged sectional view on the line 3—3, Fig. 1.

Fig. 4 is a fragmentary sectional view similar to Fig. 3 but drawn to a still larger scale and showing the slide as shifted to another position.

Fig. 5 is an enlarged sectional detail as on the line 5—5, Fig. 1, and showing also a tray supporting bar on the side wall of an incubator.

Fig. 6 is an enlarged fragmentary top plan view.

And, Fig. 7 is a sectional detail on the line 7—7, Fig. 4.

Similar reference numerals refer to similar parts throughout the several views.

In the drawings the numeral 1 represents a rectangular frame between opposite sides of which extend a plurality of partition members which, in this instance, are regularly spaced longitudinally extending wire rods 2 forming rows for receiving the eggs which are placed end to end in such rows. Secured to the under face of the frame 1 in any suitable manner, as by nails, not shown, is a bottom 3 of comparatively thin sheet material, and, as a reinforcement for this bottom, metal strips 4 are provided. These strips, two being shown in the drawings, extend transversely of the frame 1 and have their ends 5 turned upwardly against the outer faces of the front and rear frame pieces and secured thereto by screws 6, each strip in turn being reinforced by being formed for the greater part of its length into an angle bar 7, the juncture of the two inclined faces lying against the bottom member 3.

Slidably supported upon the perforated bottom 3 and beneath the wires 2 is a transversely movable egg supporting slide 8, preferably of like perforated sheet material as the bottom 3 but having the elongated perforations extending at right angles to those in the bottom 3 so that for any position of the slide the perforations in the bottom will not be closed and, also, this arrangement will permit an easier movement of the slide in the event of any burr being left on either of the perforated members.

This slide 8 is of less width than the inner width of the frame 1 so as to permit a forward and back movement sufficiently, when moved in one direction or the other, to effect a simultaneous turning of the eggs a desired amount about their longitudinal axes, the eggs, on movement of the slide, being caused to rotate due to their contact with the partitioning wires or rods 2. The frame 1 is undercut along its inner bottom edge to provide a channel 9, the side edges of the slide being guided in the channeled side frame pieces, while the front and rear edges of the slide enter the portions of the channel 10 in the front and rear frame pieces, respectively, as such slide is moved forward or back to turn the eggs.

Secured to the slide at the center of its forward edge is an operating member 110

which, in this instance, is an upstanding finger engaging rod or bolt 10 having its inner end riveted into a reinforcing plate 11 soldered to the slide. When the slide is moved inwardly this rod 10 acts as a stop by engaging one of the wires 2, and when the slide is drawn forward the rod or finger piece 10 enters a notch 12 in the front frame piece, this slot being protected around its upper edge by an escutcheon plate 13.

The wood pieces of the frame 1 are quite narrow so that, for any given outside dimensions for the tray, a maximum area will be provided for receiving the eggs which are placed in all of the rows formed by the partition wires 2 and the front and rear frame pieces, the front and rear edges of the slide 8 engaging under the eggs in the first and last rows as the slide is moved forward and back.

In order to add finish and a flat under surface to the tray, and also an additional support for the thin perforated bottom 3, a second frame member 14, of like outer length and width as the frame 1, is secured to the under face of the frame 1 by fastening devices as the nails 15, the frame pieces of this under part 14, it will be noticed, being wider but of less depth than those of the frame 1, while the supporting strips 4 are clamped between the two frame members with the angle bar portions 7 of such strips lying in the open space of the frame 15.

From the foregoing it will be seen that I have provided an egg tray of rigid and inexpensive construction and having a maximum capacity for given outside dimensions. Also, rods are provided for keeping the eggs properly spaced and which co-operate with a manually operable egg supporting slide for effecting a simultaneous even turning of all the eggs.

In using the tray, eggs are placed end to end in the several rows formed by the partitioning wires 2 and the tray placed in an incubator, a side wall of which is indicated at 16, upon supporting cleats or bars 17, after which, for a certain number of days, the eggs are periodically turned over by moving the slide 8 back or forth by engaging the operating member 10.

What I claim is:

1. In an egg tray for incubators, the combination with a rectangular frame the side pieces of which are undercut along their inner bottom edges to form channels, of regularly spaced longitudinally extending partition members secured to the frame above said channels, a perforated bottom on the frame, a transversely movable perforated slide supported on said bottom and of less width than the inner width of the frame, and means for operating the slide, the side edges of the slide being guided in said channels.

2. In an egg tray for incubators, the combination with a rectangular frame having an undercut channel around its inner bottom edge, of regularly spaced longitudinally extending partition members secured to the frame above said channel, a perforated bottom on the frame, a transversely movable perforated slide supported on said bottom and of less width than the inner width of the frame, and means for operating the slide, the side edges of said slide being guided in the undercut side frame pieces, while the front and rear edges of the slide enter the undercut front and rear frame pieces on forward and back movement, respectively, of the slide.

3. In an egg tray for incubators, the combination of two superposed rectangular frame members, the opening in the under frame being smaller than that of the upper frame and the inner bottom edge of the latter being undercut, a perforated bottom interposed between the two frames and forming the bottom of a channel in the under face of the upper frame, a perforated egg supporting slide transversely movable over said bottom and being of less width than the inner width of the upper frame, such slide being guided in opposite sides of said channel, means for operating said slide, regularly spaced longitudinally extending partition members secured to said upper frame, and supporting members for said bottom secured to one of said frames.

4. In an egg tray for incubators, the combination of two superposed rectangular frame members of like outside dimensions, the frame pieces of the bottom member being of greater width than those of the top member, the inner bottom edge of the top member being undercut, a perforated bottom interposed between the two frames and forming the bottom of a channel in the under face of the top frame, a perforated egg supporting slide transversely movable over said bottom and being of less width than the inner width of the top frame, such slide being guided in opposite sides of said channel, means for operating said slide, regularly spaced longitudinally extending partition members secured to said top frame, and supporting members for said bottom secured to one of said frames.

5. In an egg tray for incubators, the combination of two superposed rectangular frame members of like outside dimensions, the frame pieces of the bottom member being of greater width than those of the top member, the inner bottom edge of the top member being undercut, a perforated bottom interposed between the two frames and forming the bottom of a channel in the under face of the top frame, a perforated egg supporting slide transversely movable over said bottom and being of less width

than the inner width of the top frame, such slide being guided in opposite sides of said channel, means for operating said slide, regularly spaced longitudinally extending partition members secured to said top frame, and supporting members for said bottom, such members comprising strips in-

terposed between the two frames with their ends secured to opposite outer side faces of one frame and having intermediate portions 10 bent to form angle bars, substantially as set forth.

EDWIN O. BRANINGTON.
